ROTARY HOOK

George R. Wainwright, Glendale, Calif., assignor,
by mesne assignments, to William H. Maxwell,
Los Angeles, Calif.

Application October 2, 1944, Serial No. 556,723

8 Claims. (Cl. 112—228)

1

This invention has to do with a rotary hook of a sewing mechanism, that is, with an assembly of elements for handling a bobbin in a lock stitch type sewing machine, and it is a general object of the invention to provide improvements in the mounting of a bobbin case base in a hook unit and an improved arrangement and relationship of hook unit, bobbin case base and thread guard.

Sewing mechanisms or bobbin handling mechanisms employed in lock stitch type sewing machines involve essentially a hook unit, a bobbin case base, a bobbin case carried by the base and in turn supporting the bobbin proper, and a thread guard. It is advantageous in practice to support the bobbin case base in the hook unit so that there is a certain amount of freedom of movement between these elements and it is also desirable to have the thread guard supported so that it is rigid with the hook unit.

It is a general object of my present invention to provide a structure of the general character hereinabove referred to wherein the bobbin case base is yieldingly supported in the hook unit so that there is a certain limited clearance or freedom of movement between these parts that will free foreign matter that might otherwise tend to jam the mechanism or interfere with free operation.

It is another object of this invention to provide a mechanism of the general character referred to having a yieldingly supported bobbin case base in combination with a thread guard which is rigidly supported from the hook unit. With the construction that I have provided the hook unit supports or forms a base for both the bobbin case base and the thread guard, but the bobbin case base and thread guard are mounted on the hook unit to be entirely independent of each other.

Another object of the present invention is to provide a simplified and improved yielding support for a bobbin case base. The structure of the present invention involves a single spring element which yieldingly retains the bobbin case base in place in connection with the hook unit, this single spring being the only part or element that moves or operates to allow shifting of the bobbin case base relative to the hook unit. By employing a single spring element I obtain a uniform action which is difficult, if not impossible, to obtain with a plurality of separate spring units or with mechanisms that involve a series of connected parts subject to variations.

The various objects and features of my invention will be fully understood from the following

2

detailed description of a typical preferred form and application of the invention, throughout which description reference is made to the accompanying drawings, in which:

5 Fig. 1 is a side elevation of a mechanism provided by my present invention. Fig. 2 is a face or front view of the mechanism shown in Fig. 1. Fig. 3 is a sectional view taken as indicated by line 3—3 on Fig. 2. Fig. 4 is a transverse sectional view being a view taken substantially as indicated by line 4—4 on Fig. 3. Fig. 5 is an enlarged detailed sectional view showing marginal or flange portions of the hook and the bobbin case base at a point to show the mounting of 10 the guard from the hook unit. Fig. 6 is an enlarged detailed sectional view showing marginal or flange portions of the hook unit and bobbin case base at a point to show the manner in which these parts are connected and Fig. 7 is an enlarged detailed sectional view of the connection 15 shown in Fig. 6 taken at the screw shown therein and in a direction normal to the plane of Fig. 6.

The mechanism in which my present invention 20 is incorporated involves, generally, a hook unit A, a bobbin case base B, a bobbin case C, a bobbin D, means E yieldingly retaining the bobbin case base in the hook unit and a thread guard F supported from the hook unit independently of the 25 bobbin case base and the means E. These various essential elements are normally assembled together as a unit or mechanism to be carried on the end of a shaft, the bobbin case base being supported in the hook unit, the bobbin case being 30 supported in the bobbin case base B and the bobbin in turn being supported in the case C. The means E serves to yieldingly retain the base B in the hook unit A while the guard F is supported directly on the hook unit A to surround 35 the projecting portion of the bobbin case base without in any way contacting it or interfering with its movement or action.

Since my present invention is primarily concerned with the mounting of the bobbin case base 40 B in the hook unit A through the means E and with the thread guard F and the manner in which it is mounted on or supported from the hook unit A in relation to the bobbin case base B, I will confine my description largely to these parts or 45 features of the construction and will only make general reference to other structural features of the mechanism which may, in practice, be features such as are common to or conventional in mechanisms of this kind.

55 The hook unit A is the basic part of the mecha-

nism and is the member or element by which the mechanism is supported from an operating shaft. In the preferred form, as shown in the drawings, the hook unit involves, generally, a forwardly opening or facing cup-like body 10 and a mounting hub 11. The body 10 includes an inner end wall 12 which projects radially from the forward end of the hub 11 and a peripheral side wall 13 which projects forward from the outer edge portion or margin of the end 12. The hub 11 projects rearwardly from the end 12 and is provided with a central bore 14 to receive an operating shaft and has a tapped opening 15 to carry a set screw for securing the mechanism on a shaft. In addition to the parts thus far described the hook unit includes or is provided with a flange 16 which projects radially from the rim or forward end of the side wall 13, which flange is finished to have a flat smooth forward front face 17. In the preferred construction the several parts of the hook unit are formed integrally, that is, they are formed as a single continuous integral unit, as shown throughout the drawings.

The bobbin case base B is a cup-like element supported partially in the hook unit A to be concentric therewith and to face forward or in the same direction as the hook unit. In its preferred form the bobbin case base involves, generally, an inner end 18, an annular side wall 19 projecting forward from the peripheral edge or margin of the end wall 18, and a mounting flange 20 projecting radially from the side wall 19. The flange 20 of the bobbin case base is located about midway between the two ends of this unit, that is, it is located to project from the middle portion of the side wall 19 and it is provided to support the bobbin case base B in or from the hook unit A so that there is a thread passage or channel 21 between these units or elements of the mechanism, as clearly shown in Fig. 3 of the drawings.

The bobbin case base B facing downwardly, as above described, forms a receptacle or carrier that receives the bobbin case C in which the bobbin D is mounted. The bobbin case C includes, generally, a forward end or flange 22 and a rearwardly extending side wall 23 proportioned to fit into the opening or cavity of the bobbin case base. The bobbin D is arranged within the case C on a central hub 24 provided in the case so that it is confined between the wall 18 of the bobbin case base and the wall 22 of the bobbin case. In the drawings I have shown a central spindle 25 in the bobbin case base entering the hub 24 of the bobbin case and in practice any suitable means or mechanism may be incorporated in the structure for retaining the parts just described in the proper assembled relationship.

In accordance with the construction that I have provided a recess or channel 30 is provided in the corner formed where the side wall 13 and flange 16 of the hook unit join. This channel 30 is formed concentric with the axis of the mechanism and is shaped and proportioned to receive or accommodate the flange 20 of the bobbin case base. The radial extent of the channel is such as to receive the flange 20 with working clearance and the depth or axial extent of the channel is made substantially equal to the thickness of the flange 20 so that when the bobbin case base is in the normal position in the hook unit A the outer side 31 of the flange 20 lies in the same plane as the outer side or face 17 of the flange 16 of the hook unit A. The means E

which I have provided for retaining the bobbin case base B in the hook unit A or in other words for retaining the flange 20 in the channel 30 involves a single spring. This spring is a flat or leaf spring arcuate in form, being formed on a center concentric with that of the flange 16 and extending around through an angle of substantially 280°. The main portion or body 40 of the leaf spring is proportioned so that it is substantially as wide as the face 17 of the flange 16 between the channel 30 and the outer edge 41 of the flange.

The spring is secured or made fast to the face 17 of the flange 16 at spaced points, preferably 15 at two spaced points as I have shown in the drawings, this being sufficient to hold the spring in place and to gain the action desired as herein-after described. In the drawings I have shown the spring fastened to the face 17 at two spaced 20 points by means of screws 43 which pass through openings 44 in the spring and thread into tapped openings 45 in the flange, the heads 46 of the screws being engaged over the spring to clamp the spring to the face 17 of the flange. Where 25 the spring is arcuate, as I have described, and extends through about 280° I can advantageously locate the screws or points of fastening about 65° from the ends of the spring so that they occur about 126° apart. It is to be noted that 30 the spring is mounted through the screws 43 so that the gap or opening between its two ends occurs opposite or in register with the thread handling parts of the mechanism or, in other words, at the thread channel which enters the hook unit 35 A so that the spring in no way interferes with the thread handling action of the mechanism.

In accordance with my invention I provide inwardly projecting lips 47 on the spring to overhang or overlie the outer side 31 of the flange 40 of the bobbin case base. The lips serve to retain the flange 20 in the groove 30 and they are proportioned and located on the body 40 of the spring so that they retain the flange 20 in the groove 30 with the desired resilience. Where 45 the spring is arcuate and proportioned about as I have described and where it is fastened at two points, as by two screws 43 as I have described, I find it practical to provide one lip 47 on the inner edge of the spring between the two screws and lips outward of the screws and extending to the ends of the spring. With this arrangement I have three spring lips 47 retaining the flange 20 in the channel 30 and these lips are spaced around the flange so that the retention is substantially uniform. In practice I may make the spring 40 flat or I may crimp or corrugate it slightly at each side of each screw to give it added resilience or flexibility. Crimps or bends 50 such as I have just referred to are shown in Fig. 7 of the drawings.

The thread guard F extends around the front or forward end portion of the mechanism thus far described, so that it is located in front of the assembled flanges 16 and 20 surrounding the 65 forwardly projecting portion of the bobbin case base B. In the particular form of construction illustrated the guard, as shown in Fig. 2, is flat and corresponds generally in size and shape to the flange 16 of the hook unit and has an opening 60 sufficiently large to pass the forward or projecting portion of the bobbin case base with clearance. In accordance with my invention I support the thread guard F from the flange 16 of the hook unit and I preferably provide a plurality of points of support for the guard so that

the guard is supported firmly in spaced relation immediately forward of or in front of the assembly of the flanges 16 and 20 and the spring of means E.

In the preferred construction I provide three points of support for the thread guard and each of these supports involves a screw 61 carried in an opening 62 in the flange 16 of the hook unit and threaded in an opening 63 in the guard and a spacer in the form of a collar 64 surrounding the screw and bearing between the face 17 of the flange 16 and the inner side of the thread guard. The spacer is proportioned to space the thread guard away from the spring of the means E so that there is the desired clearance between these parts, as shown throughout the drawings. The spacers may be separate from the guard or they may be fastened or joined thereto, in which case they may be threaded so that the screws 61 thread into them, as well as into the guard, as shown in the drawings. The screws 61 enter the openings 62 from the rear face of the flange and their heads 67 are preferably countersunk into the flange, as shown in the drawings.

In accordance with my invention the mounting of the thread guard from the flange 16 is entirely independent of the support or retention of the flange 20 in the channel 39. In order to prevent interference between these various elements I provide the spring of the means E with openings 70 which pass the guard supports with clearance, that is, openings sufficiently large to pass the spacers 64 with suitable clearance, as clearly shown in Fig. 5 of the drawings. Where I provide three supports for the thread guard, as shown in the drawings, I locate one midway between the two screws 43 and one at or near each outer end of the spring of means E. This gives the thread guard support at three points about equally spaced around the structure which, in practice, is ample.

In addition to the parts thus far described the mechanism may include features or elements common to this class of mechanism, for instance, at the desired point around the flange 16 it may be fashioned to present a forwardly facing thread engaging tongue 80 and immediately forward of the tongue in the direction of rotation of the mechanism, the hook unit has an inwardly and rearwardly extending thread passing notch or channel 81. Further, the thread guard at its inner edge portion may be cut away at 82 and formed to leave a forwardly projecting offset thread engaging tongue 83 which overlies and registers with the tongue 80 of the hook unit and projects from the guard to catch the thread. These various parts may be proportioned or fashioned in the manner common to mechanism of this kind so that they serve or function in the manner common to mechanisms of this character. In like manner the mechanism may include a recessed tongue 90 projecting from the bobbin case base B and a tongue 91 projecting from the bobbin case to cooperate with the tongue 90 and a thread tensioning spring member 92 may be provided in connection with the tongues. In practice these elements can be varied as circumstances require, as my invention is in no way concerned with them but is confined to the features and combinations of construction which I have indicated.

From the foregoing description it will be apparent that I have provided a construction whereby the bobbin case base B is effectively and dependably supported in the hook unit A to

operate most effectively and yet it is yieldingly held or supported so that it will free or clear foreign matter that would otherwise tend to jam the mechanism. Likewise, it will be apparent that I have provided a construction of the general character referred to having a thread guard of a most advantageous type or form guarding the structure by which the bobbin case is retained in the hook unit and that this thread guard is mounted so that it is in a definite predetermined position relative to the hook unit and is entirely independent of the mounting of the bobbin case base in the hook unit. The thread guard presents a smooth surface over which the thread rolls or slides while being passed around the bobbin case and provides a guard for the means E. With the construction that I have provided I have minimized danger of improper operation due to minor misalignment of parts. For instance, should there be a slight misalignment or imperfection in the thread guard it will not in any way interfere with or disturb the proper action or functioning of the bobbin case base and likewise the bobbin case base is free to function and may clear itself of foreign matter without in any way interfering with or putting strain upon the thread guard.

It is also to be noted that I have provided a construction whereby the several screws involved can be mounted or set tight to eliminate danger of working loose without danger of binding or setting any of the parts so that their operation is impaired.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. In a mechanism of the character described, a cup-like hook unit, a bobbin case base supported in the said unit, and a single leaf spring yieldingly retaining the said base in the said unit, the spring being attached to the unit and having circumferentially spaced lip parts projecting from its inner edge yieldingly engaging the base.
2. In a mechanism of the character described, a hook unit, a bobbin case base supported in the unit, means yieldingly retaining the base in the unit, and a thread guard supported on the unit at the front of the unit opposite said means and independent of the said means.
3. In a mechanism of the character described, a hook unit having a flange at its forward end, a bobbin case base supported in the unit at the flange, means carried by the flange yieldingly retaining the base in the unit, and a thread guard supported at the forward end of the unit and from the flange independent of said means.
4. In a mechanism of the character described, a hook unit having a flange at its forward end, a bobbin case base supported in the unit at the flange, a leaf spring carried by the flange yieldingly retaining the base in the unit, and a thread guard supported at the forward end of the unit and from the flange independent of the said leaf spring.
5. In a mechanism of the character described, a hook unit having a flange at its forward end, a bobbin case base supported in the unit at the flange, a leaf spring carried by the flange yieldingly retaining the base in the unit, a thread guard at the forward end of the unit free of the base,

and spaced supports mounting the guard from the flange independent of the spring.

6. In a mechanism of the character described, a hook unit having a flange at its forward end, a bobbin case base supported in the unit at the flange, a leaf spring carried by the flange yielding-ly retaining the base in the unit, screws fixing the spring to the flange at spaced points, a thread guard at the forward end of the unit free of the base, and spaced supports mounting the guard from the flange independent of the spring.

7. In a mechanism of the character described, a hook unit having a flange at its forward end, a bobbin case base supported in the unit at the flange, a leaf spring carried by the flange yieldingly retaining the base in the unit, a thread guard at the forward end of the unit free of the base, and spaced supports mounting the guard from the flange independent of the spring, the spring having openings passing the said supports with clearance.

8. In a mechanism of the character described, a hook unit having a flange at its forward end, a

bobbin case base supported in the unit at the flange, a leaf spring carried by the flange yieldingly retaining the base in the unit, a thread guard at the forward end of the unit free of the base, and spaced supports mounting the guard from the flange independent of the spring, the spring having openings passing the said supports with clearance, the supports including spacers between the guard and the flange and screws joining the flange and guard.

10 ing the flange and guard.
GEORGE R. WAINWRIGHT.
